UNITED STATES PATENT OFFICE.

JACOB TELLER, OF CHICAGO, ILLINOIS.

DESIGN FOR A GAS HEATER.

Application filed February 12, 1929. Serial No. 30,030. Term of patent 7 years.

To all whom it may concern:

Be it known that I, JACOB TELLER, a citizen of the United States, and a resident of Chicago, in the county of Cook and State of Illinois, have invented a new, original, and ornamental Design for a Gas Heater, of which the following is a specification, reference being had to the accompanying drawing, forming part thereof.

The figure is a perspective view of a gas heater, showing my new design.

I claim:

The ornamental design for a gas heater, as shown.

JACOB TELLER.
